UNITED STATES PATENT OFFICE.

JOHN T. CORLEY, OF PROVIDENCE, RHODE ISLAND.

DESIGN FOR A STEERING-COLUMN BRACE.

52,429.

Specification for Design.

Patented Sept. 17, 1918.

Application filed May 31, 1918. Serial No. 237,647. Term of patent 7 years.

To all whom it may concern:

Be it known that I, JOHN T. CORLEY, a citizen of the United States, residing at Providence, in the county of Providence, State of Rhode Island, have invented a new, original, and ornamental Design for a Steering-Column Brace, of which the following is a specification, reference being had to the accompanying drawing, forming a part thereof, in which—

Figure 1 is a plan view illustrating my new design;

Fig. 2, a side view; and

Fig. 3, a section on the line A—A of Fig. 1.

I claim:—

The ornamental design for a steering column brace as shown.

JOHN T. CORLEY.

Copies of this patent may be obtained for five cents each, by addressing the "Commissioner of Patents, Washington, D. C."
